[57] ABSTRACT

The pedal comprises a rigid frame having a pair of spaced parallel legs, each of which includes upper and lower out-turned protective flanges flanking a web portion of the leg; the web portion carries a permanently anchored reflector element protected by the out-turned flanges. Over each leg and reflector element is telescoped an internally channeled extruded tread member or block to be engaged by the foot of a cyclist.

CYCLE PEDAL WITH ANCHORED REFLECTOR

CROSS-REFERENCES TO RELATED
APPLICATIONS

Related applications are identified as follows:

Carlton P. Paswsat, et al., Ser. No. 56,291, filed July 20, 1970.

BACKGROUND OF THE INVENTION

Cyclists using vehicular roads and highways at night, have been the victims of collisions resulting from inability of other vehicle drivers to discern the presence of cyclists in dim light. To reduce the frequency of such collisions, reflectors have been applied to cycles in various ways, including the mounting thereof upon the cycle pedals in such manner as to project areas of reflected light to the vision of approaching vehicle drivers. The need for improvements in the mounting of reflectors on cycle pedals is recognized herein.

DESCRIPTION OF THE PRIOR ART

The prior art is best illustrated in the Carlton P. Paswsat, et al. patent application, Ser. No. 56,291, filed July 20, 1970, which discloses cycle pedals having reflector elements which are secured relative to the pedal frame solely by means of engagement with portions of a tread member carried by the pedal frame. While such pedals are highly efficient, damage to the tread member of such a nature as to cause or result in loss or removal of the entire tread member per se from the pedal frame could result in separation of the reflector from the pedal structure.

SUMMARY OF THE INVENTION

The reflector element as herein disclosed, is permanently fixed to the frame of the pedal, rather than to the tread member, so that wearing away or mutilation of the tread member, or loss thereof in its entirety, will not defeat the effectiveness of the reflector element to flash reflected light warnings during use of the cycle. The reflector element, formed preferably of one or more strips of acrylic resin or equivalent plastic material, may embody integral studs for insertion into holes formed in the pedal frame web, which studs thereafter may be upset and headed at their free ends to provide a permanent anchorage upon the pedal frame. Studs or fasteners in other forms may be employed for anchorage purposes, if desired.

In an alternative construction illustrated, the pedal frame web may be window apertured to receive an embossed portion of the reflector element, while the back of the element is held by a retainer strap riveted or otherwise secured to the pedal frame. In any case, the reflector element cannot be rendered functionally ineffective by loss or displacement of the tread member from the pedal frame.

DESCRIPTION OF DRAWINGS

FIG. 1 is a perspective view of a cycle pedal embodying the present invention.

FIG. 2 is an exploded perspective view of the same.

FIG. 3 is a side elevational view of the pedal.

FIG. 4 is a cross-section taken on line 4—4 of FIG. 3.

FIG. 5 is a view similar to FIG. 4 showing a modification.

FIG. 6 is a side elevational view of a pedal in further modified form.

FIG. 7 is a cross-section taken on line 7—7 of FIG. 6.

FIG. 8 is a view similar to FIG. 7, showing a modification thereof.

FIG. 9 is an exploded perspective view showing another modification.

FIG. 10 is a side elevational view of the pedal of FIG. 9.

FIG. 11 is a cross-section taken on line 11—11 of FIG. 10.

FIG. 12 is a cross-section taken on line 12—12 of FIG. 10.

DESCRIPTION OF THE PREFERRED
EMBODIMENTS

In the drawings, the numeral 16 indicates generally the cycle pedal frame, which comprises a rigid metal stamping formed to provide spaced parallel legs 18, 18, and a connecting base or strut portion 20. The base or strut portion 20 may be suitably ribbed as at 22 for purposes of reinforcement and rigidity, and may carry a central dome or cap 24 adapted to cover or protect the outer pedal bearing which usually is confined in a raceway 26. A second bearing cover 26 may be provided for the inner bearing of the pedal, as is usual. The pedal shaft or axle is denoted 28, and may terminate as a screw-threaded stud 30 attachable to the crank or hanger of the drive sprocket, not shown.

The pedal frame legs 18, 18, disposed in spaced parallelism, are rigidified by means of upper and lower outwardly extended flanges 32, 34, which may extend substantially the full length of the legs. The intermediate portion of each leg may be referred to as the web or main wall 36 of the pedal frame. The flanges 32, 34 are of substantial width, but preferably are not as wide as the width dimension of the web. The reinforcing ribs 22 of strut 20 may extend partly into the webs 36, 36 as shown.

The free ends of webs 36, 36 may be developed to provide tangs 38, 38 which are receptive in slots 40, 40 of a connecting bar 42 that carries bearing cover 26. The tangs may be bent over or twisted to lock the bar 42 onto the ends of the webs or arms of the pedal frame, (FIG. 1).

It is important to note that the pedal frame flanges 32, 34 are turned outwardly relative to the axis of pedal shaft 28, and are parallel thereto. The out-turned flanges are utilized to advantage for protecting the reflector element and prolonging its useful life, as well as that of the tread member 44. This outward turning of

the flanges causes them to overlie and underlie the reflector, and thereby buffer the reflector against twisting and compressive forces directed onto the tread member incident to vigorous pedaling or braking of the cycle.

The tread member or pedal block may be approximately as long as a pedal frame leg, 18, and may be generally rectangular of cross-section. It may be ribbed longitudinally as shown, to minimize slippage. The tread member may be molded, extruded, or otherwise formed of a plastic or rubber-like material having a measure of inherent resiliency and flexibility, by preference.

Each tread member 44 may be formed with a longitudinal internal channel 46 shaped and dimensioned complementarily to the cross-sectional shape and size of a pedal leg 18, so that the tread member may be slid or telescoped onto the pedal leg, substantially into end abutment against strut 20. Each pedal leg may be so sheathed with a tread member, after which the bar 42 and its associated shaft and bearing parts may be applied to the tanged ends of the pedal legs according to FIGS. 1 and 3. The channel 46 includes angularly disposed branches 48, 48 receptive of the outwardly turned leg flanges 32 and 34. The base of channel 46 is defined by a rear wall 50 of the tread member.

The channel branches 48, 48 are defined each by a lip 52 formed from the material of the tread member, said lips being directed toward the rear wall 50. The lips may be coextensive in length with the length of the tread member. Further, the lips are spaced from one another along their length, in substantial parallelism, to provide an elongate window 54 through which a reflector element may be exposed, as will be explained in greater detail hereinafter.

The reference numeral 56 indicates generally a reflector, or reflective element, which may be in the form of a strip of plastic material such as acrylic resin, or equivalent suitable material treated to possess light-reflective properties. It may be a laminated element, or a strip in one piece, as desired.

In accordance with the disclosure of FIGS. 1 through 4, the reflector element 56 comprises two coextensive laminations of plastic strip material bonded together in face contact, said laminations being denoted 58 and 60. The strip 58 is translucent, and is adapted for exposure through window 54. Strip 60 is a backing strip of plastic material formed with one or more integral plastic studs 62 which are deformable by the action of heat and pressure. Light reflective substance may be carried by one of the laminations 58 or 60, for exposure through the translucent lamination 58. The laminations are to be chemically compatible for proper bonding.

The web 36 of each pedal leg is provided with holes 64 spaced apart and dimensioned to receive the plastic lugs 62 of the reflector element, with member 60 resting flatly against web 36 between the flanges 32, 34. Such placement of the reflector element then may be followed by application of heat and/or pressure upon the free ends of the inserted lugs, causing formation of an enlarged head 66 (FIG. 4), which secures the reflector element permanently to the frame web. After fixation of reflector elements upon the webs of both legs 18, 18 as above stated, the tread members may be telescoped over the frame legs to encase the legs and their attached reflector elements, resulting in the assembly of FIG. 4, wherein the reflector element is visible through window 54.

As FIG. 4 clearly indicates, the lips 52, 52 defining the window 54 bear against the flanges 32 and 34, and against also the longitudinal edges of the reflector element, to preclude dirt and moisture from reaching the back of the reflector element and the interior of the tread member.

It may here be noted that wear or damage inflicted upon the tread member 54 (FIG. 4), even to the extent of its complete displacement from leg 18, will not reduce the effectiveness of reflector element 56 in the

performance of its intended function, because of the anchorages at lugs 62 which retain the reflector element upon the pedal frame.

FIG. 5 shows a slight modification of FIG. 4, indicating that the reflector element can be constructed of a single strip of material carrying the deformable lug 68 which corresponds to lug 62 of FIG. 4. Lug 68 may be headed as at 66 by the application of heat and/or pressure, according to previous explanation.

The modification illustrated by FIGS. 6 and 7, is distinguished by the fact that the composite or bi-part reflector element 56 (FIG. 7) carries no deformable lugs. Instead, the reflector element is drilled or apertured transversely to receive one or more rivets 70 or equivalent fasteners adapted to enter the holes of web 36. After insertion of the rivets through the web holes, the rivets may be peened to establish the anchorage heads 72.

FIG. 8 is distinguished from FIG. 7 only in the provision of a one-piece reflector element 56, secured to web 36 by means of rivets or equivalent fasteners as disclosed in explaining FIG. 7.

The modification, FIGS. 9-12, proposes the formation of an enlarged elongate aperture 74 in each web 36, flanked by a pair of holes 76, 76 which are receptive of rivets or equivalent fasteners 78, 78. The elongate aperture 74 is adapted to accommodate the embossed forward face portion 80 of a reflector element which includes an enlarged base portion 82. The base portion meets the reduced face portion to provide opposed parallel shoulders 84, 84 to abut the rear face of the web marginally of aperture 74. Thus, the reflector element may be partially confined by aperture 74.

To hold the reflector element in place, and to secure it upon web 36, an elongate metallic strap 86 is provided. The strap spans the length of the reflector element, and has end portions 88, 88 reaching beyond it to overlie the web adjacent to the opposite ends of aperture 74. The end portions 88, 88 of the strap carry apertures 90, 90 to register with web holes 76, 76 and their respective fasteners 78. The anchorage of the reflector element is effected by placing strap 86 against the back of reflector base 82 while the reflector is supported in web aperture 74, and then inserting and setting the rivets 78 in apertures 76 and 90. The strap being thereby secured against web 36, it anchors the reflector element in web aperture 74 permanently and securely, so that the reflector element will remain in place upon the pedal frame irrespective of the presence or absence of a tread member such as 44.

As will be understood, the reflector element 80 could be furnished in several short sections, rather than as one long section, without altering the anchorage means of FIGS. 9 and 10. Also, the reflector element may be of either the laminate construction, or the one-piece construction previously referred to herein.

What is claimed is:

1. A bicycle pedal comprising a rigid pedal frame, an inner end plate and a shaft, the frame being of U-shaped configuration, the base being the outer end plate and the legs having the inner end plate connected thereto at the free end thereof, the shaft extending through the inner end plate and into a bearing carried by the base of the frame, the legs of the frame comprising a vertical web with flanges extending outwardly

normal to each longitudinal edge of the web, pedal tread blocks mounted on the legs, the pedal blocks having a channel therethrough, the channel having a base portion and outwardly extending branch portions adjacent each longitudinal edge of the base portion, the configuration of the legs of the pedal frame fitting in the configuration of the channel in the pedal block, the pedal block being maintained on the legs of the pedal frame and being prevented from rotation on the longitudinal axis thereof, the pedal block having an outwardly facing side with a longitudinal opening therein, upper and lower wall portions of the opening extending toward the web and being inwardly of the branch portions of the channel, the opening extending the full length of the pedal block, the opening being of less width than the distance between the flanges of the legs a light reflective element within the opening and being adjacent the web, and means permanently securing the reflector to the web.

2. A cycle pedal as defined in claim 1, wherein the reflector is secured to the central web of the frame leg at a location between the said outwardly extending flanges thereof.

3. A cycle pedal as defined in claim 1, wherein the means for permanently securing the reflector to the central web of the leg frame includes an opening through said web into and through which a stud integral with the reflector projects.

4. A cycle pedal as defined in claim 1, wherein the means for permanently securing the reflector to the central web of the leg frame comprises one or more fastener members which extend through aligned apertures in the reflector and web.

5. A cycle pedal as defined in claim 1, wherein the web of the leg frame includes an elongate aperture dimensioned to receive a forwardly projecting portion of the reflector with a peripheral portion of the reflector engaging the rear surface of the central web adjacent said aperture; means overlying and engaging the rear surface of the reflector, and means permanently securing said last mentioned means to the rear surface of said web beyond the aperture therein.

6. A cycle pedal as defined by claim 1, wherein the means for securing the reflector element comprises at least one fastener which passes through the web and its adjacent reflector element.

7. A cycle pedal as defined by claim 1, wherein the means for securing the reflector element comprises an aperture formed in the web, said reflector element including a deformable stud having an end insertable through said aperture, said stud end after insertion being enlarged to preclude withdrawal of the stud from said aperture.

8. The combination as defined by claim 1, wherein the means for securing the reflector element comprises an elongate opening in the web dimensioned to receive therein a portion of the reflector element; and a back-up strap secured to the web in substantial flat-wise

abutment upon the reflector element, for pressing said element against said web.

9. The combination as defined by claim 8, wherein the back-up strap securement is located near opposite ends of the reflector element.

10. The combination as defined by claim 9, wherein said back-up strap securement is located outside the limits of the reflector element.

11. The combination as defined by claim 8, wherein the reflector element includes a pair of shoulders along opposite side edges thereof adapted to abut the frame leg marginally of the elongate opening, for stabilizing the position of the reflector element relative to said frame leg.

15. 12. In a cycle pedal construction, the combination which comprises: a pedal frame rotatable about an axis and including a pair of spaced substantially parallel elongate legs of approximately equal length each having a free end, a pair of spaced substantially parallel rigid flanges, and a web intermediate said flanges; said flanges of each leg being turned outwardly from the pedal axis to define an outer face of the web, said web including an opposite back face; a pair of flexible elongate tread members substantially coextensive in length with the length of the legs, said tread members each having formed therein an elongate open-ended channel receptive of the web and having branches receptive of the outwardly turned flanges of the web; said outwardly turned flanges of the web overlying and underlying an intermediate portion of the tread member material to intercept and absorb forces directed laterally onto the tread member by the foot of a cyclist; a window aperture in the tread member between said flanges; A reflector element and means for fixing said reflector

20. 30. 35. element comprising an aperture formed in a frame leg; said reflector element carrying a deformable stud having an end insertable through said aperture, said stud end after insertion being physically deformed to preclude withdrawal of the stud from said aperture.

40. 13. The combination as defined by claim 12, wherein the means for fixing each reflector element comprises an elongate opening in the frame leg dimensioned to receive therein a portion of the reflector element; and a back-up strap secured to the frame leg in substantial flatwise abutment upon the reflector element, for pressuring said element against said leg.

14. The combination as defined by claim 13, wherein the back-up strap securement is located near opposite ends of the reflector element.

50. 15. The combination as defined by claim 14, wherein said back-up strap securement is located outside the limits of the reflector element.

55. 16. The combination as defined by claim 13, wherein the reflector element includes a pair of shoulders along opposite edges thereof adapted to abut the frame leg marginally of the elongate opening, for stabilizing the position of the reflector element relative to said frame leg.
